UNITED STATES PATENT OFFICE.

CARL A. ANDERSON, OF VISTA GRAND, CALIFORNIA, ASSIGNOR OF ONE-HALF TO EDWARD M. STEHN, OF SAN FRANCISCO, CALIFORNIA.

NON-REFILLABLE BOTTLE.

No. 922,998.

Specification of Letters Patent.

Patented May 25, 1909.

Application filed October 1, 1908. Serial No. 455,773.

To all whom it may concern:

Be it known that I, CARL A. ANDERSON, a subject of Sweden, residing at Vista Grand, in the county of San Mateo and State of California, have invented new and useful Improvements in Non-Refillable Bottles, of which the following is a specification.

My invention relates to non-refillable bottles. Its object is to provide a simple, cheap, 10 practical bottle, and stopple attachment therefor, by which the contents of the bottle may be readily removed, but which will effectually prevent the refilling of the bottle after it is once emptied.

15 The invention consists of the parts and the construction and combination of parts as hereinafter more fully described and claimed, having reference to the accompanying drawings, in which—

20 Figure 1 is a sectional view of the invention. Fig. 2 is a perspective of the valve. Fig. 3 is a section on line X—X. Fig. 4 is a section on line Y—Y.

A represents a bottle or container of any 25 suitable size, shape and material, to which the invention is applicable. The neck of this bottle is preferably screw-threaded, or otherwise provided with means for allowing the insertion of the stopple member or plug 30 2 into it and the securing of the stopple to be locked therein. I prefer to screw the plug into the neck of the bottle, and to provide the periphery of the plug or stopple with a spring latch or equivalent means, as 35 3, engaging in a specially provided recess 4 in the neck of the bottle. Thus, while the stopple can be easily screwed into place in the neck, and made to seat down on a shoulder 5 inside the neck, the moment the latch 40 3 engages in the notch 4, the stopple is prevented from ever being removed.

The stopple may be made of glass, porcelain, or any other suitable material, and is chambered out to provide a central outlet 45 passage 6 communicating with ports 7 which extend at each side of a bridge 8 which is preferably triangular in cross-section, as shown in Fig. 1. The ports 7 converge again to a central passage 9 which opens 50 into a valve chamber 10 wherein a valve member 11 is slidable. This valve member 11 is preferably rectangular, and it is transversely grooved on top, as shown at 12, correspondingly with the side grooves 13 in the 55 side walls of the valve chamber 10. The

bottom of the valve is preferably concaved and adapted to seat on a beveled ledge 14 surrounding the orifice 15 which opens into the bottle. The valve seat portion 14 is made separate from the body 2 of the stopple, so as to allow of the insertion of the valve into the valve chamber; this valve seat being screwed or otherwise secured into the lower end of the stopple. The grooves 13 in the side walls of the valve chamber 60 65 terminate at the top of the valve seating ring, and the valve is adapted to fit into a socket in the seat, so that when the valve is resting on the seat 14 no liquid can pass down through the various channels and 70 ports in the stopple and enter the bottle.

In operation, the bottle is first filled, and then the stopple, which has the valve and valve seating ring 14 first assembled in position, is screwed into the neck of the bottle, 75 or otherwise permanently anchored therein. The orifice 6 may then be closed by a cork 16 or other suitable seal.

To empty the contents of the bottle, it is only necessary to remove the cork 16 and 80 invert the bottle, whereupon the liquid will flow out through the orifice 15, down the side ports 13, through groove 12 to orifice 9, thence through ports 7, around the bridge 8, and out through the orifice 6. Righting 85 the bottle allows the valve 11 to fall back on its seat and prevents the bottle from being filled.

Having thus described my invention, what I claim and desire to secure by Letters Patent is—

In a non-refillable bottle, a stopple member having a circuitous central passageway, said passageway having an enlarged portion forming a rectangular valve chamber and said valve chamber having grooves in its opposite walls, a rectangular valve sliding in said chamber, and the top of the valve having a transverse groove communicating with the grooves in opposite walls of the 95 valve chamber, said valve having a seat in the valve chamber at the end opposite said groove.

In testimony whereof I have hereunto set my hand in presence of two subscribing witnesses.

CARL A. ANDERSON.
